UNITED STATES PATENT OFFICE.

WILLIAM COLLIER JAMES, OF PLYMOUTH, ENGLAND.

DESIGN FOR BLACK-LEAD BLOCKS.

Specification forming part of Design No. 5,045, dated June 27, 1871.

To all whom it may concern:

Be it known that I, WILLIAM COLLIER JAMES, of Plymouth, county of Devon, England, have invented and produced a new and original Design for Blocks of Black Lead, of which the following is a specification:

The nature of my design is fully represented in the accompanying illustration, to which reference is made; and my invention consists in the shape or configuration of a dome, *a*, as applied to the manufacture of blocks of black-lead or plumbago in solid blocks *b*, which shape, as applied to this purpose, is my invention, and which I have introduced to the trade under the name of "dome black-lead."

The above-named shape or configuration is

more particularly shown in the drawing hereto annexed, and I consider the form given to the said block or blocks to be an improvement upon the shape of the blocks in which black lead is now manufactured in solid blocks, since the form given to the block by me renders it less liable to fracture during transportation and when in use. It also has a more elegant appearance.

I claim as my invention—

The design for blocks of black lead, having a dome, *a*, and body *b*, substantially as herein shown and described.

WILLIAM COLLIER JAMES.
